(57) **CLAIM**

The ornamental design for a violin shoulder rest, as shown and described.

DESCRIPTION

FIG. 1 is a perspective view of the violin shoulder rest; FIG. 2 is a side view of the violin shoulder rest;

FIG. 3 is a top plan view of the violin shoulder rest;

FIG. 4 is a bottom plan view of the violin shoulder rest;

FIG. 5 is a left side view of the violin shoulder rest;

FIG. 6 is a right side view of the violin shoulder rest; and,

FIG. 7 is a top perspective view.

The broken lines shown throughout the views represent the portions of the design which form no part of the claim.
